UNITED STATES PATENT OFFICE.

JOHN R. ANDERSON, OF MOLINE, ILLINOIS, ASSIGNOR OF ONE-HALF TO JOHN MORD-HORST, OF ROCK ISLAND, ILLINOIS.

CLOTHES-LINE STRETCHER.

1,276,702.

Specification of Letters Patent. Patented Aug. 27, 1918.

Application filed October 29, 1915. Serial No. 58,559.

To all whom it may concern:

Be it known that I, JOHN R. ANDERSON, a citizen of the United States, residing at Moline, in the county of Rock Island and 5 State of Illinois, have invented certain new and useful Improvements in Clothes-Line Stretchers, of which the following is a specification.

This invention relates to a clothes line 10 stretcher and has for its object the provision of a simple and inexpensive device which may be applied to the line at any convenient point and which is readily operable to remove the slack from the line.

15 Various objects and advantages of my invention will be apparent as it is better understood by reference to the following specification when read in connection with the accompanying drawing, illustrating a preferred embodiment thereof, in which

Figure 1 is a plan view of the device according to my invention and

Fig. 2 is a side elevation thereof.

As is well known considerable difficulty 25 is experienced by the average person in stretching clothes lines so that they will not sag, and particularly where lines are fixed permanently in position, they vary in length owing to atmospheric conditions, so that it 30 is frequently desirable to remove the slack therefrom.

I have, therefore, devised the present structure which, referring to the drawing, comprises end members 1 and 2 connected 35 by the rods 3. Rotatably mounted in the yokes 4, formed preferably integral with the end member 2, are rollers 5 adapted to be engaged by the line 6 and to form guides therefor. A screw 7 is rotatably mounted 40 in the end members 1 and 2 and provided with an operating handle 8, a nut 9 being preferably disposed on the screw 7 adjacent the end member 1 to retain the screw in operative position. Slidably mounted on the 45 rods 7 is a member 9' having a hook portion 10 preferably formed integral therewith, the portion 10 being adapted to engage the line 6 between the rollers 5 so that as the member 9' is moved longitudinally of the frame along

the rods 3 a loop 11, consisting of the slack 50 portion of the line, will be formed. The member 9' threadedly engages the screw 7 and as the screw 7 is rotated by the operating handle 8 the member 9' may obviously be moved in either direction along the rods 3. 55

The operation of my device should be apparent without further description of the structure thereof. When the line 6 has been placed in position the member 9' is moved by means of the screw 7 to a position adjacent the end member 2 and the line 6 is disposed over the rollers 5 and around the hook portion 10 of the member 9'. The handle 8 is then operated to move the member 9' toward the end member 1 so that the loop 11 60 65 is formed as previously described.

In practice the device is constructed so that the member 9' has a movement of approximately six inches, whereby a slack portion amounting to twelve inches may be 70 quickly and effectively taken up. Obviously, however, the exact dimensions of the device are immaterial since it may be made larger or smaller as the conditions under which it is to be used vary. 75

It will be readily appreciated that I have devised a simple and inexpensive structure which is admirably adapted to accomplish the desired results with a minimum of effort, particularly since the device may be 80 applied to the line at any point in the length thereof.

It will be apparent that various changes may be made in the form, construction and arrangement of the parts without departing 85 from the spirit and scope of the invention, or sacrificing any of its material advantages, the form hereinbefore described being merely a preferred embodiment thereof.

I claim:

In a clothes line stretcher, the combination of a frame comprising end members and a pair of separate rods disposed therebetween and secured thereto, a slidable member provided with openings embracing said rods and having a medially disposed hook formed integrally therewith to engage the line midway between said rods, a screw 90 95

2
journaled in said end members and threadedly engaging said slidable member, a nut on said screw bearing against one of said end members to retain said screw in operative position, an operating handle connected to said screw whereby the latter may be rotated to move said slidably mounted member

longitudinally of the frame, and guiding rollers on one of said end members to support the line on both sides of said hook.

JOHN R. ANDERSON.

Witnesses:

HARVEY E. BROWN,

VERNON G. SWANSON.
